UNITED STATES PATENT OFFICE.

PAUL F. WILLIAMS, OF CHICAGO, ILLINOIS, ASSIGNOR TO G. & W. ELECTRIC SPECIALTY CO., OF CHICAGO, ILLINOIS, A CORPORATION OF ILLINOIS.

POT-HEAD CONNECTOR.

1,335,542.

Specification of Letters Patent. Patented Mar. 30, 1920.

Application filed March 15, 1910. Serial No. 549,490.

To all whom it may concern:

Be it known that I, PAUL F. WILLIAMS, a citizen of the United States, residing at Chicago, in the county of Cook and State of Illinois, have invented a certain new and useful Improvement in Pot-Head Connectors, of which the following is a full, clear, concise, and exact description, reference being had to the accompanying drawings, 10 forming a part of this specification.

My invention relates to pot-head connectors and discloses a different species of the invention described and claimed in my Patent No. 1,154,823, issued September 28, 1915. 15 My invention is designed for use with pot-head connectors and provides a construction in which a bowl is used for the entering cable and wherein the cable is separated into its component conductors, which bowl is 20 provided with a removable cover having a plurality of diverging outlets for the individual conductors, which outlets are symmetrically arranged with respect to the axis of the cover.

25 More particularly my invention contemplates improved constructional features for establishing the interconnection between the cable conductor and the aerial conductor, which is to be associated therewith in connection with a removable cover device as set forth.

30 I will describe my invention more in detail by reference to the accompanying drawing, illustrating the preferred embodiment 35 thereof in which:

Figure 1 is a side view partly in section of my improved pot-head connector,

And Figs. 2 and 3 are details of construction.

40 Referring more particularly to Fig. 1, I show a body portion 1 of the pot-head, which body portion I prefer to call a bowl which is adapted for mounting on any suitable support. The bowl is bent so that its inlet 45 and outlet are angularly displaced ninety degrees. This I find to be of great advantage when cables run horizontally into the pot-head, from whence they are distributed as aerial conductors.

50 The cable inlet 2 accommodates the cable 3 which has conductors 4, 5, and 22^a, an adapter 6 being interposed for cables of different size.

The bowl 1 has a removable cover 12,

which through the interposition of a suitable gasket 7, is held in place by adjustable bolts 8. Ears 9 are provided to support the pot-head in place. Outlets 10 are fastened to the cover 12, which outlets are of insulating material, and through which the 55 conductors 4, 5 and 22^a are to pass. The conductors 4, 5 and 22^a are at first soldered or otherwise fastened in place in a double sleeve or socket 11. The insulation of the conductor is removed for this purpose as 60 shown.

The aerial conductor is also fastened in a sleeve 13, which sleeve has screw threaded engagement with a tubular resilient connecting device 14 secured thereto in addition 65 by a screw 15 passing through a wall 14^a in member 14. An insulating cap 16 carries the sleeve 13 and has associated therewith a rotatable adjuster 17 of insulating material, held in place by lugs 18 provided 70 upon a conical sleeve 19. This conical sleeve engages a conical surface at the upper extremity of the member 14. Members 10, 16 and 17 together form an insulator within 75 which the devices for connecting the cable conductor to the aerial conductor are housed.

When the insulating cap 16 with its associated aerial conductor is to be placed in contact with the conductor 5, the extension 14 is inserted in the cylindrical member 11 80 and the element 17 rotated, which on account 85 of its slotted interior surface rotates the lugs 18, and thereby the conical element 19 which permits this motion, by virtue of the screw threaded element 11. The lugs 18 engage 90 for this purpose the slots 24. This tends to push the element 14 very securely into the double sleeve 11 and securely contact the members 19 and 14 thereby making 95 a joint of high conductivity. The element 14 is constructed to produce a spring-like connecting means and the element 19 in connection with the member 17 forms wedging means for pressing the spring conducting means into place.

100 These auxiliary means for bringing the conductors tight together are necessary when pot-heads for current conductors of high carrying capacity are to be used. The element 17 as shown more clearly in Figs. 2 105 and 3 may be provided with projections 20, upon the surface so that said projections may be easily grasped to rotate said element;

or openings 21 may be left as shown more clearly in Fig. 3, which would provide the necessary holding surface.

Countersunk screws 22 are used more thoroughly to hold the outlets 10 in place and prevent them from turning. A fiber gasket 23 is interposed for cushioning purposes. A nipple 25 is left at the top of the insulator 16, so that insulating tape may readily find lodgment thereon.

It will be seen that as said auxiliary element 17 alone is rotated, when fastening the conductors together, the insulator 16 will not be rotated and the insulating tape, thus, will not be disturbed. Compound 26 is used to fill in the spaces after the parts are in proper position.

While I have herein shown and particularly described the preferred embodiment of my invention, I do not limit myself to the precise construction and arrangement as herein set forth, but having thus described my invention, what I claim as new and desire to secure by Letters Patent is:

A pot head comprising a bowl, a plurality of tubular insulating members projecting upwardly from the top of said bowl, the lower ends of said insulating members being open to the interior of the bowl, rotary insulating members mounted upon the tops of said projecting insulating members, said rotary members being adapted for rotation relatively to said insulating members, caps mounted upon the rotary insulating members, said caps having their upper ends provided with apertures to receive conductors to be connected, and also to receive insulat-

ing material for hermetically sealing said conductors in position, connecting devices within said projecting tubular members and the rotary members and caps mounted thereupon, said connecting devices being adapted to be operated so as to permit or prevent their separation by the relative rotation of said rotary members, and insulating material located within the bowl and extending up also into the tubular members projecting from the top thereof, said insulating material being adapted to hermetically seal conductors located in the bowl and also to extend up into the projecting members to hermetically seal the same, and the portions of the connecting devices located in the upper ends of said projecting members, said relatively rotary members being provided with overhanging portions which serve to protect the upper ends of the projecting members from the elements and also to provide a means whereby said members may be rotated and said caps being provided with downwardly extending portions which overhang the upper ends of the relatively rotary members whereby said members have their upper ends protected against the elements and also whereby the same may be rotated to operate the connecting devices therein.

In witness whereof, I hereunto subscribe my name this 9th day of March, A. D. 1910.

PAUL F. WILLIAMS.
